NEW VITAMIN B₁₂ FACTOR

Konrad Bernhauer, Aschaffenburg (Main), and Hans-werner Dellweg, Stockstadt (Main), Germany, assignors, by mesne assignments, to Merck & Co., Inc., Rahway, N.J.

Filed July 22, 1957, Ser. No. 673,433

Claims priority, application Germany July 21, 1956

1 Claim. (Cl. 260—234)

The present invention relates to the production and recovery of a new vitamin B₁₂ factor, and more particularly to a new "incomplete" vitamin B₁₂ factor.

It is possible to differentiate between the "complete" and the "incomplete" forms of the compounds under the B₁₂ series. The "complete" compounds consist of the cobalt-containing basic complex and a nucleotide. Three different possible "incomplete" forms containing the basic complex are possible as shown in the following structural formulas (Formulas I, II, and III) and compared with the structural formula of the "complete" factor (Formula IV).

I

Aetiocobalamin (without nucleotide)

II

Aetiocobalamin-phosphoric acid (without nucleoside)

III

Aetiocobalamin-phosphoric acid-ribose (without base)

2

IV

"Complete" B₁₂ factor (without nucleotide)

15 The complete structural formula of Product III, with which the present invention is concerned, is as follows:

20 30 35 40 45 Of the possible "incomplete" B₁₂ factors the only one known prior to the present invention is vitamin B₁₂ factor B (aetiocobalamin—Formula I). As may be seen from the structural formulas, this compound differs from the complete factor (Formula IV) only in the lack of a nucleotide. The other two theoretically possible factors were unknown prior to the present invention.

50 It is therefore a primary object of the present invention to provide for the production of a new "incomplete" vitamin B₁₂ factor.

55 It is another objective of the present invention to provide a new method for the production of the new "incomplete" vitamin B₁₂ factor of the present invention.

It is more particularly the basic object of the present 60 invention to provide for the production of an "incomplete" vitamin B₁₂ factor corresponding to the Formula III shown above.

Other objects and advantages of the present invention will be apparent from a further reading of the specification and of the appended claim.

With the above objects in view, the present invention mainly consists in a new composition of matter having a structural formula corresponding to Formula III above.

The novel features which are considered as characteristic for the invention are set forth in particular in the appended claim. The invention itself, however, with respect to the method thereof will be best understood from the following description of the method when read in conjunction with the accompanying drawings in which a flow sheet illustrating the method of the present invention is set forth.

Sewage sludge, which as is known, serves as the source material for the production of vitamin B_{12} and other vitamin B_{12} factors (German Patent No. 922,126) can also serve as the source of the compound of the present invention.

The method of the present invention comprises a special combination of various steps each of which per se may be known with the final purpose of producing the new product of the present invention which is herein designated as "aeticobalamine-phospho-ribose." The attached flow sheet indicates the individual method steps of the method of the present invention, the following description more fully describing the steps.

In accordance with the method of the invention digested sewage sludge is first treated with about 0.1% of sulfur dioxide, the pH is adjusted to about 6.5 and the mass is heated to temperature of 80° C. About 0.5% of ferric chloride is added and the mass is centrifuged. The centrifugate is acidified to a pH of 3.0, the pH is then adjusted to 6.5 to cause flocculation of colloidal substances and this mass is again centrifuged. The clear filtrate is mixed with 0.5% of activated carbon and the material is again centrifuged. The carbon adsorbate (solid material) is then eluted several times with a 1:1 mixture of water and isopropanol at about 70° C. The material is again centrifuged and the eluate concentrated under vacuum.

The eluate concentrate is then purified by extraction, for example with phenol-*o*-dichlorobenzol. The purified extraction concentrate is precipitated on kieselguhr by means of a phenol and this crude "kieselguhr product" is subjected to a first column chromatography on cellulose with secondary butanol and water, containing potassium chlorate and hydrogen cyanide. This results in separation of the new factor of the present invention between the vitamin B_{12} and vitamin B_{12} factor III zones. This new factor is then precipitated on kieselguhr by means of a phenol and subjected to a second column chromatography on cellulose with water-saturated *n*-butanol plus hydrogen cyanide to obtain the purified new factor of the present invention.

This purified new factor is subjected to electrophoresis at pH 6.5 in cellulose. The fraction which migrates to the anode is the new vitamin B_{12} factor of the present invention. This fraction is eluted with phosphate buffer and subjected to a first chromatography on aluminum oxide. The eluate is evaporated under vacuum and the residue precipitated with zinc chloride at a pH of 8.5.

After filtration and washing the filtrate is treated with ammonium sulfate and extracted with benzyl alcohol, the new factor is transferred into water and precipitated on kieselguhr by means of phenols. This material is then subjected to a second chromatography on aluminum oxide, the eluate is evaporated under vacuum, the residue taken up in methanol, precipitated with acetone, subjected to suction filtration and then dried to obtain the new factor of the present invention.

The new vitamin B_{12} factor of the present invention produced as described above has the following properties:

The compound is a violet colored rather hygroscopic powder.

The absorption spectrum at pH 6.5 in the presence of cyanide ions is identical with the spectrum of aetico-

balamine (Formula I). The molar extinction at 367 m μ $E_{mol}=30.59 \times 10^8$.

The following are the R_f -values in the indicated developer systems:

- 5 0.31 in G (sec. butanol saturated with water-0.01% HCN saturated with $KClO_4$);
- 10 0.31 in H (sec. butanol-100, water-50, glacial acetic acid-1-0.005% HCN);
- 15 0.33 in I (sec. butanol-100, water-36, 25% NH_3 -14-0.005% HCN).

Paper electrophoresis: pH 2.7—neutral, orange; pH 6.5—monobasic acid, violet.

The distribution coefficient equals 1 in the system of *n*-butanol aqueous ammonium sulfate solution with 6.5% ammonium sulfate (dicyano form).

The analysis and structure determinations of the new factor of the present invention yield the following:

By decomposition with 70% perchloric acid factor B is obtained, which can be identified by chromatographic and electrophoretic methods.

Decomposition by means of cerium hydroxide results in factor B (identified as above) and d-ribose, which can be identified by paper chromatography.

- 25 The cobalt content was determined by the method of J. M. Chilton (Anal. Chem. 25, 1247, 1953). The phosphate content was determined according to the method of C. H. Fiske, Y. Subbarow (Methods of Biochem. Anal., Interscience Publishers Inc., New York 1954, vol. I, S. 99). The ribose content was determined by means of the orcin reaction in accordance with the method of A. H. Brown (Methods of Biochem. Anal., Interscience Publishers Inc., New York 1954, vol. I, page 298).

From these determinations it is concluded that the new factor of the present invention consists of 1 mol of factor B plus 1 mol of phosphoric acid plus 1 mol of ribose combined and that the compound has a molecular weight of 1255.23. The compound may therefore be designated as "factor B-phospho-ribose" (or "aeticobalamine-phosphoribose").

The new compound of the present invention has an activity of 13.5 γ /opt. E. against *E. coli*. The new factor can be decomposed into factor B, which in usual manner can be converted by biosynthesis into vitamin B_{12} itself or other vitamin B_{12} factors whereby it is possible to make additional use of the new factor of the present invention.

The following example will further illustrate the method of producing the new compound of the present invention. The scope of the invention is of course not meant to be limited to the specific details of the example.

Example

55 8 cubic meters of digested sludge, obtained by the methane fermentation of sewage sludge, after the addition of 0.1% SO_2 and the adjustment of the pH value to 6.5 is heated at 80° C. After the addition of 0.5% ferric chloride the solid material is centrifuged off, the centrifugate is clarified by acidification to pH 3.0 and flocculated turbidity-forming substances are eliminated after again adjusting the pH value to 6.5.

60 The obtained aqueous solution having a volume of 7.5 cubic meters is treated for adsorption of the vitamins of the B_{12} group with activated carbon. After obtaining the adsorbate by centrifugation the adsorbate is eluted at a temperature of about 70° C. with a mixture of equal parts of isopropyl alcohol and water.

65 The obtained eluate (about 900 liters) is concentrated under vacuum to a volume of 100 liters. The further purification proceeds by countercurrent extraction with *o*-dichlorobenzol and *p*-chlorophenol in the same manner as described in German Patent No. 961,023, namely in a four-stage process in which the concentrated eluate is extracted in the first stage with the solution of a halogenized phenol in a liquid hydrocarbon, or with a halo-

genized hydrocarbon, or with other solvents such as carbon disulfide, or a mixture of such solvents; the thus obtained organic phase is then washed in the second stage with buffered solutions within the pH range 2-8.5, and with distilled water whereafter the vitamins are transferred in the third stage from the organic to the aqueous phase by addition of an oxygen-containing polar substance such as acetone and washed in the fourth stage with a suitable organic solvent which is immiscible with water. The obtaining of the "kieselguhr product" is in accordance with the publication of W. Friedrich and K. Bernhauer (Z. Naturforsch. 9b, 755, 1954), whereby the oily vitamin B₁₂-phenol complex is accepted by kieselguhr, forming a homogeneously red colored product which precipitates easily, whereby the supernatent liquid becomes clear. The kieselguhr product can be easily sucked off and washed with phenol-saturated water.

The column chromatography of the kieselguhr product no cellulose with a mixture of 77% sec. butanol, 23% water, 0.05% hydrocyanic acid saturated with potassium perchlorate (in accordance with German Patent No. 944,216) results in a violet band of the new factor between the zones of vitamin B₁₂ and vitamin B₁₂ factor III. The corresponding eluate from the column is again precipitated on kieselguhr and subjected to chromatography on a cellulose slurry column utilizing water-saturated n-butanol as the developer. This results in a further separation from vitamin B₁₂ and vitamin B₁₂ factor III.

The fraction of the new factor which still contains some vitamin B₁₂ and vitamin B₁₂ factor III as impurities (7350 opt. E.) is subjected to an electrophoretic separation. This is carried out in a cellulose column having a diameter of 60 mm. and a height of 400 mm. at 750 volts and 150 to 200 milliamperes with 0.0166 molar of phosphate buffer at a pH of 6.5 during a time period of 12.5 hours. Under these conditions the new factor quickly migrates to the anode while vitamin B₁₂ and vitamin B₁₂ factor III because of electroosmosis migrate weakly to the cathode. The column is subsequently eluted with phosphate buffer.

After the addition of 6 times the amount of acetone to this solution the new factor (5400 opt. E.) is absorbed on an aluminum column from which it is again eluted with a mixture of 70 parts acetone and 30 parts water. After concentration of the eluate under vacuum the residue is taken up in 200 cc. of water, mixed with 6 g. of zinc chloride and the pH value of the solution is adjusted to 8.5 by means of sodium hydroxide. The resulting precipitate is filtered off by suction over kieselguhr and thoroughly washed with water. After the addition of 60 g. of ammonium sulfate to the red filtrate (300 cc.) the new factor is extracted with a total of 150 cc. of benzyl alcohol, the alcoholic extract mixed with chloroform and again extracted with water.

After an additional chromatography on aluminum oxide with acetone-water (80:20) as eluting agent, the obtained solution is evaporated to dryness under vacuum, the residue taken up with 10 cc. of methanol and this mixed with 150 cc. of acetone. This results in flocculation of the new factor of the present invention which after standing for 3 hours at a temperature of

-2° C. is completely flocculated. The obtained violet product is filtered off under suction with complete exclusion of air moisture, and it is then dried under vacuum over magnesium perchlorate.

The yield amounts to 234 mg., the purity of which is 65.14% calculated on the cobalt content and related to a molecular weight of 1255.23.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claim.

What is claimed as new and desired to be secured by Letters Patent is:

As a new composition of matter, aeticobalamine-phosphoric acid-ribose having the following structural formula:
